UNITED STATES PATENT OFFICE.

BENJAMIN F. JOHNSON, OF TROY, NEW YORK.

IMPROVEMENT IN COOKING-STOVES.

Specification forming part of Letters Patent No. 92,055, dated June 29, 1869.

To all whom it may concern:

Be it known that I, BENJAMIN F. JOHNSON, of the city of Troy, county of Rensselaer, and State of New York, have invented a new and useful Improvement in Cooking-Stoves having tanks for heating water attached; and I hereby declare the following to be a full and exact description of the same, reference being had to the accompanying drawings, and to the letters of reference marked thereon, making a part of this specification.

The object and scope of my said invention is to be found in so constructing the back and the flue or flues of a cooking-stove, in connection with a water-tank, as to be able to pass the escaping products of combustion in such a manner as to heat the oven through the back of the same, or to send such products against the side of the water-tank to heat the water therein; or to so direct the said products, heated air, &c., as to heat the oven and tank at the same time, thereby adapting the use of the stove and water-tank to any desirable operation, either for heating the oven or the water. The improvement, as represented in the accompanying drawings, is set out as applied to a three-flue stove, but it is neither my purpose nor intention to limit the application of my said invention to stoves of any particular number of flues, as the same may be applied to stoves of one or more flues.

I apply my improvement to cooking-stoves by means of the form and construction of the back of the stove, which may be composed of a single recessed plate or of several plates, forming recesses for the flues and rests for the water-tank.

In Figure 1, *a* is the back plate or plates of the stove, as the case may be. *a' a'* are rests formed by the projections of the lower half of the back plate *a*, which assist the eyes *h h* and hooks *h' h'* of Fig. 2 in supporting the water-tank *A* when attached to the stove, as shown in Fig. 3. *b'* is a damper for regulating the passage of the products of combustion through the flues *f*, said damper being adjusted by the connecting-rod *c'*.

The recess, as shown in Fig. 1, is designed to make provision for the middle or center flue when a three-flue stove is used. In such case an additional plate, *d*, Fig. 4, is required to be used to form the back of the flue up to

the bottom of the tank or to the rests *a' a'*, which additional plate *d* is shown in position in Fig. 6. This mode of constructing the lower part of the flue *f'*, Fig. 1, increases largely the capacity of said flue in the stove below the tank, which flue becomes or may become divided in the upper part thereof by means of the plate *e*, so attached as to form a part of the back plate of the stove.

By substituting the plate *e'* for the plate *d*, the back of the stove is made complete without the use of the water-tank.

In the construction of cooking-stoves having water-tanks attached to the rear or back of the stove, provision should always be made to so control the escaping products of combustion, together with the heated air, &c., on their way to the chimney, as to use them altogether for heating the oven, or altogether for heating water in the tank, or for both purposes simultaneously. This I have accomplished by my arrangement, construction, and combination, as herein set forth; and by means of the dampers in the flue, as seen at *b*, Fig. 1, I can cause the entire draft to pass up on the oven side of the plate *e*, thereby causing more heat to come in contact with that part of the oven-back composed of the plate *a* in the back of the flue-recess than otherwise would; or by means of the same damper *b* I can cause the entire draft to pass up in the tank side of the plate *e*, for the purpose of heating more rapidly the water in the tank, or by leaving the damper *b* partially open I can divide the draft, sending a part up on the oven side and a part up on the tank side of said plates. This damper *b* is managed by means of the connecting-rod *c'*, as seen in Fig. 3.

The recessed form of the back plate *a a a*, &c., presents two lateral recesses for the side flues in the back of the oven, as they appear at *f* in Fig. 7. These lateral flues and the back of the oven are completed by means of plates like Fig. 8, *f'*, which are seen in position at *f' f'* in Fig. 3.

The upper part of the flue is constructed by means of the collar or semi-collar *c*, Fig. 5, and the concave in the tank. The shape of *c* is seen at Fig. 5, and is seen in position at Fig. 3 in connection with the tank *A*.

It will be perceived, by an examination of

Fig. 6 that the back of the oven and front of the upright flues in the back of the stove may be cast in a single piece, and in the usual manner, and the lateral and middle flues may be in part constructed in the usual manner, except as herein stated. The extreme back plate of the stove may be cast in two parts, thus: The lower half of said back plate in Fig. 6, represented by the parts marked *a d a*, may be cast together, forming a single plate, and the upper half of said back plate may be cast together, forming the plate *a' e a'*, as seen in Fig. 6.

When the boiler, Fig. 2, or the tank, with its semi-flue recess *f*, is attached by means of its hooks *h h'*, through the recesses *h h*, as seen in Fig. 6, and the semi-collar *e*, Fig. 5, is in its place, the stove and tank are combined and ready for use. That part of the back of the stove represented by plate *e*, Fig. 6, divides the upper part of the middle flue into two parts, each of which may be used separately or together, as circumstances may require. As already set forth, the appropriate use of the front or back half of this middle flue will be regulated by the damper *b* in Fig. 1.

If stoves of but one back (shut) flue are used, the back plate of the stove may be cast in two parts, as suggested in Fig. 6, so that the lower half of the back plate may project outward two inches or more beyond the lower edge of the upward half, forming an opening two or more inches in width, nearly or quite across the back of the stove, in which case the boiler or tank flue *f'*, Fig. 2, will be formed by extending the same in breadth equal to the width of the opening in or between the said two back plates of said stove. Thus two flues will be formed, as in Fig. 6, one between the back plate of the stove and the back plate of the oven, and the other between the back

plate of the stove and the side of the water-tank; and said flues will be regulated and controlled by a damper situated and operated like *b* in Fig. 1.

Having thus fully described my said invention and improvement, and the several modes of applying the same, I will next proceed to specify my claims, and what I wish to secure by Letters Patent.

I claim—

1. The back of a cooking-stove, constructed with rests and recesses, as described and shown, for the purpose set forth.
2. The combination of a water-tank with such recessed back of said stove, in the manner and for the purpose above described.
3. The division of the upper part of the flue by means of the plate *e*, or its equivalent, in combination with damper *b*, for the purpose above described.
4. The division of the said flue by the plate *e* in Fig. 6, in combination with the flue *f* in the tank *A*, Fig. 2, for the purpose herein described.
5. The two parts of the back plate of the stove, *d* and *e*, in combination with the flue-opening between them, for the purposes herein described.
6. Said several parts of the back plate of a cooking-stove, and the flue-opening between the same, in combination with the water-tank *A*, constructed and arranged in the manner and for the purposes herein described.
7. The plate *e'*, to complete the stove without the combination of the water-tank, substantially as described.
8. The damper *b*, in combination with the plates *d* and *e*, substantially as described.

BENJAMIN F. JOHNSON.

In presence of—

JOEL TIFFANY,
S. V. HEWES.
